UNITED STATES PATENT OFFICE

169,304

PAIR OF GOGGLES

Robert L. Decot, Snyder, N. Y.

Application September 5, 1951, Serial No. 16,520

Term of patent 14 years

(Cl. D57—1)

To all whom it may concern:

Be it known that I, Robert L. Decot, a citizen of the United States, residing at 167 Hamilton Drive, Snyder, in the county of Erie and State of New York, have invented a new, original and ornamental Design for a Pair of Goggles, of which the following is a specification, reference being had to the accompanying drawing, forming part thereof.

Fig. 1 is a front elevational view of a pair of goggles, showing my new design;

Fig. 2 is a top plan view thereof; and

Fig. 3 is a side elevational view thereof.

The dominant features of my design are shown in solid lines in the drawing.

I claim:

The ornamental design for a pair of goggles, as shown and described.

ROBERT L. DECOT.
